UNITED STATES PATENT OFFICE.

JOHN ZORN, OF DETROIT, MICHIGAN, ASSIGNOR OF ONE-THIRD TO DAVID WALLACE, OF SAME PLACE.

PAINTER'S STRIPING-TOOL.

SPECIFICATION forming part of Letters Patent No. 514,984, dated February 20, 1894.

Application filed November 2, 1893. Serial No. 489,828. (No model.)

To all whom it may concern:

Be it known that I, JOHN ZORN, a citizen of the United States, residing at Detroit, county of Wayne, and State of Michigan, have invented a certain new and useful Improvement in Painter's Striping-Tools; and I declare the following to be a full, clear, and exact description of the invention, such as will enable others skilled in the art to which it pertains to make and use the same, reference being had to the accompanying drawings, which form a part of this specification.

This invention relates to tools employed to produce stripes or lines in decorative painting, decorative kalsomining and the like.

It has for its object an improved form of tool by which either a straight, curved, or broken line may be produced easily and formed with great regularity, without requiring that peculiar skill which has been hitherto required in doing work of this kind.

The tool embodying this invention is used as a storage for the color to be employed, and is arranged to permit the colored liquid to escape gradually and regularly when the tool is used.

In the drawings, Figure 1 is a perspective of a tool designed to draw a single line. Fig. 2 shows the disassembled parts of a tool arranged to draw two parallel lines. Fig. 3 is a side elevation of a tool adapted to draw two parallel lines, with an intermediate wavy or curved line.

A indicates a cup, having at its mouth opening a flange B, extending outward around the edge of the cup, and extending inward toward the middle in a flange C, the two flanges B and C forming a tabular support for a disk of felt or similar substance, D.

E indicates a cup precisely similar to the cup A, provided with external flange F corresponding to the flange B, and an internal flange corresponding to the flange C. The two flanges B and F are circular in their external peripheries, and concentric to their peripheries is an axle G that extends through them and forms the axle on which or with which they revolve. Preferably, the axle G is screw threaded, and provided with two nuts, c and d, although one of these may be dispensed with, and one of the cups may be

secured to the axle if desired; or, in place of a nut, a collar may be secured to the axle.

In assembling the parts, the two cups are placed on the axle with the flanges B and F adjacent to each other, and with the disk D interposed between them. One of the cups, E, is provided with a filling hole, e, adapted to be closed by a cork or other suitable stopper, and the two cups, with the interposed disk D, are filled with the coloring material to be used for striping purposes. The opening between the flanges is then adjusted so that the mat D lies loosely between them, leaving a thin opening on one or both sides of the mat D between it and the flanges, through which the coloring material can slowly ooze or trickle. In this condition, the tool is ready for work, and can be used for drawing straight lines without any other attachment whatever. For overhead work, however, it is desirable that a handle, H, be attached to the tool, in order that the coloring surface of the disk D may roll on the object to be striped. For work that is below the tool or on side walls, a sufficient quantity of the coloring material would ooze through to keep what may be called the painting or brush part constantly filled with the color; but, for overhead work, the color would fall away from the felt striping surface, and it is consequently desirable that the tool rotate, to present a freshly charged surface at all times to the wall above it. For this purpose, the ends of the axle G are journaled in bearings in the handle H. I prefer to make the cone bearings, as, when so constructed, the axle can be sprung in and out of the handle very easily.

When it is desired to produce parallel lines, I interpose between the cups A and E a double flanged ring K and two felt washers similar to D. If a curved or wavy line having sharp curves is desired, the flanges may be bent or regulated as indicated in Fig. 3 at f and g, and a bent or corrugated piece of felt inserted between them. It is evident that a great variety of different figures may be produced by giving to the flanges different curves, as may be desired.

The felt disk is kept in place with respect to the axle so that its outer periphery is concentric with the axle, by a number of spurs

or pins *t t t* that project from one or from both of the flanges C.

The opening through the felt disk and the opening through the flanges C is much larger than the axle, and permits the free passage of the coloring fluid between the cups A and E.

What I claim is—

1. The combination of two color holding cups arranged with their mouth openings opposite each other, and an interposed color distributing disk, substantially as described.

2. The combination of two color holding cups, an axle concentric to them, and an interposed color distributing disk, substantially as described.

3. The combination of two color holding cups, an interposed color distributing disk, an axle concentric to the cups, means for adjusting the cups on said axle, and a support for said axle.

4. The combination of color holding cups, a plurality of color distributing disks, and spacing rings interposed between the color distributing disks, substantially as described.

In testimony whereof I sign this specification in the presence of two witnesses.

JOHN ZORN.
